UNITED STATES PATENT OFFICE.

JOHN J. WIGHTWICK, OF BROOKLYN, NEW YORK.

IMPROVEMENT IN REIN-TERRETS.

Specification forming part of Letters Patent No. 151,330, dated May 26, 1874; application filed
August 30, 1873.

To all whom it may concern:

Be it known that I, JOHN J. WIGHTWICK, of Brooklyn, in the county of Kings and State of New York, have invented a new and useful Improvement in Rein-Terrets, of which the following is a specification:

The invention will first be fully described, and then pointed out in the claim.

A is the terret, made of a single piece of metal, (either cast or malleable,) having one or more rein orifices or openings, B, according to the number of horses in the team. In the bottom of this terret is, preferably, a swivel-pin, C, which passes through a bed-piece, D. The latter is screwed or riveted to the head-strap E of the bridle. The terret may, therefore, turn in either direction, and prevent the lines from tangling, besides supporting their weight and rendering it much less laborious to drive four or more horses or pairs of horses than it usually is. One of these terrets is placed, as seen, on the head of each horse in rear of the leaders, and should there be a single leader, his rein would pass through the opening F.

By means of these terrets the labor and difficulty of driving and managing a number of spans of horses in a single team are greatly lessened. The lines are supported and kept separated and prevented from tangling.

These terrets may be made very light, and, when plated or finished, present a highly ornamental appearance.

The terret may be used without swiveling on the bed-piece, and may be attached by means of ears or flanges directly to the head-strap of the bridle. I do not, therefore, confine myself to the precise arrangement shown in the drawing.

Having thus described my invention, I claim as new and desire to secure by Letters Patent—

The terret A B, swiveled on a pin, C, passing through a bed-piece, D, attached to the crown-piece of the bridle, as and for the purpose described.

JOHN JOSEPH WIGHTWICK.
